(57) **CLAIM**

I claim the ornamental design for an adapter plate for use in mounting an audio/visual device or the like to a surface, as shown and described.

DESCRIPTION

FIG. 1 is an isometric view of the claimed design.

FIG. 2 is a front elevational view of the claimed design of FIG. 1, the rear elevational view being identical thereto.

FIG. 3 is a top plan view of the claimed design of FIG. 1, the bottom plan view being identical thereto; and,

FIG. 4 is a left side elevational view of the claimed design of FIG. 1, the right side elevational view being identical thereto. The broken lines in the drawings are for illustrative purposes only and form no part of the claimed design.
